DESIGN FOR A CARAFE HOLDER

Ralph Panza, Los Angeles, Calif.

Application December 1, 1933, Serial No. 49,902

Term of patent 7 years

To the Commissioner of Patents:

Be it known that I, RALPH PANZA, a citizen of the United States, residing at Los Angeles, in the county of Los Angeles, and State of California, have invented a new, original, and ornamental Design for a Carafe Holder, of which the following is a specification, reference being had to the accompanying drawing, forming part thereof.

The figure is a perspective view of a carafe holder showing my new design.

I claim:

The ornamental design for a carafe holder, substantially as shown.

RALPH PANZA.

CERTIFICATE OF CORRECTION.

Design No. 91,786.

March 20, 1934.

RALPH PANZA.

It is hereby certified that error appears in the printed specification of the above numbered Design requiring correction as follows: Line 1, first column, for the words "To the Commissioner of Patents" read To all whom it may concern; and that the said Letters Patent should be read with this correction therein that the same may conform to the record of the case in the Patent Office.

Signed and sealed this 12th day of March, A. D. 1935.
